GARMENT FORM

Tobias Eisenberg, Philadelphia, Pa., assignor of
one-half to Morris Michael Marks, Philadel-
phia, Pa.

Application December 31, 1936, Serial No. 118,471

3 Claims. (Cl. 223—63)

My invention relates to garment forms, and it relates more particularly to forms designed for the formation, preservation, or restoration of desired creases in a garment.

The object of my invention is to provide a garment form of such character as to retain or re-establish a desired crease in a garment.

Another object of my invention is to provide a garment form of such character as to prevent the formation of undesired creases in a garment.

A further object of my invention is to provide a garment form adapted to prevent shrinkage of a garment.

A still further object of my invention is to provide a garment form which may readily be inserted in operating position within the garment, and readily withdrawn therefrom, at will.

With the above and other objects in view, my invention consists of a garment form comprising a plurality of separators, each mounted at one end thereof on a base member, and being secured at the other end thereof to a crease-forming member, said crease-forming member being substantially of the same size and configuration as that of the crease to be formed.

My invention also consists of the combination of a garment form, as hereinbefore described, with means for adjusting the lengths of the separators, and means for readily removing one of said separators, operatively to facilitate the removal of the garment form from the garment.

For the purpose of illustrating my invention, I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangements and organizations of the instrumentalities as herein shown and described.

Referring to the drawing in which like reference characters indicate like parts:

Figure 1 represents a front elevational view of a garment form embodying my invention, inserted in a garment in accordance with my invention;

Figure 2 represents a side elevational view of the garment and garment form illustrated in Figure 1, embodying my invention;

Figure 3 represents a top plan view of the garment form alone;

Figure 4 represents a perspective view of the

removable separator forming part of the garment form embodying my invention.

According to my invention I provide a base member and a crease member secured in spaced relation thereto by means of adjustable separators. However, where the garment comprises oppositely disposed creases, I preferably fabricate the base member in a manner to render it, too, a crease member.

Accordingly, with the garment form shown in Figure 1, I provide a base member 5 having a crease-forming edge 6 of the outline of the rear crease of a leg of a pair of trousers 7. This crease outline comprises an upper, waist portion 8, a rearwardly curved seat portion 9, an inwardly 15 and downwardly curved thigh portion 10, and a downwardly projecting calf portion 11.

A crease-forming member 12 is provided, with a crease-forming edge 13 disposed generally oppositely to the crease-forming edge 6 of the base member 5; said crease-forming edge 13 having substantially the same size and configuration as the crease 14 to be formed on the garment 7. In the case of a pair of trousers, the crease forming edge 13 comprises an upper, waist portion 15, 25 and a forwardly curved upper thigh portion 16, a downwardly and inwardly curved lower thigh portion 17, and a downwardly projecting calf portion 18.

Where the nature of the garment permits, as when the garment comprises bilaterally symmetrical sections, the creases of which are in relatively close juxtaposition, I may provide a base member 5' similar to the base member 5, and a crease-forming member 12' similar to the 35 crease-forming member 12.

Suitable separators 19 and 20 are provided for securing the crease-forming members to the base members and for adjustably separating the one from the other. Thus, the separator 19 comprises a female member 21 secured to the base member 5 by any suitable means, such as the screw 22. A male member 24 is secured to the corresponding portion of the crease-forming member 12 by any suitable means, such as the 45 screw 26. The male member comprises a bifurcated slide 27, and the female member 21 comprises a slide-receiving groove 28 through the face of which projects a bolt 29 adapted to pass through the space between the tines 30 and 31 of the slide 27. A thumb screw or other suitable clamping means 32 is secured to the bolt 29 by means of threading or other desired means, and is adapted to bear on the face of the slide 55

27 in a manner to clamp the slide 27 against the face of the groove 28.

The separator 20 comprises a female member 33 and a male member 34. The male member 34 comprises a bifurcated slide 35 adapted to be clamped against the face 36 of a slide-receiving groove 37 in the female member 33 in a manner similar to that of the separator 19. The female member 33 also comprises a rearwardly projecting arm 38 having a base member-receiving slot 39 having side walls 40 and 41 and rearward edges 42. Similarly, the male member 20 comprises a forwardly projecting receiving arm 43 having a crease-forming member-receiving slot 44 having side walls 45 and 46, and forward edges 47.

The separators 19 and 20 are preferably configured, as by the curves 48, 49 and 50 in a manner to facilitate a ready grip upon the various elements of the separators by the operator; 20 and to form suitable receiving notches adapted to receive and retain a hook should it be desired to suspend the garment form when in use. Thus also, the male and female members of the separators are curved as at 49 to form a hook-receiving notch between them.

In operation, the separator thumb screws 32 are loosened and the crease-forming members 12 and 12' are inserted in the legs 51 and 52 of a pair of trousers 7, and in juxtaposition to the creases 14 and 14' thereof; while the base members 5 and 5' are respectively inserted in the legs 51 and 52 in juxtaposition to the rear creases thereof; said trousers being spread upon the garment form in a manner to bring each curve of the crease-forming edges 6 and 13 in juxtaposition to the corresponding part of the trousers. By this means, the lower portions of the base and crease-forming members 5, 5', 12 and 12' pass through the normally multiple-thickness cuff portion 52 of the trousers 7. This multiple-thickness cuff portion 52 operates to spread the base and crease-forming members 5 and 12 from the corresponding base and crease-forming members 5' and 12', to a distance normally greater than the width of the separator slots 39 and 45.

The lower separator 20 is then mounted on the base members by positioning the edges 42 of the walls 40 and 41 of the base member-receiving slot 39 adjacent the outer faces of the base members 5 and 5' immediately beneath the cuff portions 52 of the trousers 7, and urging the separator 20 rearwardly against the lateral resilience of the base members 5 and 5' and the resilience of the cloth of the cuff portion 52 until the base members 5 and 5' have been guided by the edges 42 into the slot 39 and are in juxtaposition to the inner wall 53 thereof.

In like manner, the lower separator 20 is mounted on the crease-forming members 12 and 12' against the lateral resilience of the crease-forming members 12 and 12' and the resilience of the cloth of the cuff portions 52, the separator 20 being urged forwardly until the crease-forming members 12 and 12' have been guided by the edges 47 into the slot and into juxtaposition to the inner face 54 thereof. The thumb screws or other clamping means 32 are then tightened to retain the separators 19 and 20 in longitudinal adjustment.

70 By this means, the separator 20 is retained on the base and crease forming members by the lateral pressure thereof and friction thereagainst, although it is readily removed therefrom by simply sliding the separator downwardly until it passes beyond the lower edges 54 of the base

and crease forming members 5, 5', 12 and 12'; or by releasing the clamping means 32 on the separator 20, and sliding the base and crease-forming members 5, 5', 12 and 12' out of the respective receiving slots 39 and 45. By this means also, the cuff portions 52 of the trousers are stretched in a manner to remove undesired bulges and creases therein, and the inner creases 55 and 56 of said cuffs are pressed against each other in a manner to form, retain or reform said 10 creases.

Also, by virtue of the straight inner faces 53 and 54 bearing against the straight inner edges 58 and 59 of the base and crease-forming members 5, 5' and 12, 12', the garment form is rendered rigid, and incapable of pivoting about the ends of the lower separator 20 to lessen the distance between the base members 5 and 5', and the crease-forming members 12 and 12', which would result in warping the form and spoiling 20 the trousers.

If desired, I may form suitable indentations or notches 57 on the lower, inner edges 58 and 59 respectively of the base and crease-forming members 5, 5' and 12, 12', operable to serve as limiting stops by having one edge 60 of each of said notches 57, adapted to bear against the lower edges 61 of the inner face 53 or 54 of the respective base and crease-forming member-receiving grooves 39 and 45.

These notches 57 are preferably spaced from the waist portions 8 and 15 of the respective base and crease-forming members a distance equal to a measured length of trousers plus the normal distance from the lower cuff edge to the lower edges of the arms 38 and 43. Moreover, a series of notches 57 may be disposed as shown, a plurality of measured distances from the waist portions 8 and 15, to adapt the garment form for use with trousers of different leg lengths. 40 Also, if desired, suitable indicia 62 may be placed in contiguity to the respective notches to indicate the length of trouser leg with which they are adapted to be used.

When it is desired to remove the garment form 45 from the garment, the lower separator 20 is removed in the manner already described, and the base members 5 and 5' and the crease-forming members 12 and 12' are removed in one operation through the top of the trousers, by using 50 the top separator 19 as a handle and urging it upwardly.

However, if desired, the garment form may be inserted or removed in any of several manners other than that heretofore described. Thus, 55 the screw 22 may be removed from the separator 19 and the base members 5 and 5' likewise removed from the separator 19. The crease-forming members 12 and 12' are then inserted in their respective trouser legs by using the upper 60 separator 19 as a handle. The base members 5 and 5' are then separately inserted in the trousers and reassembled with the upper separators 19 by means of the screw 22. The lower separator 20 is then secured to the base and crease-forming members 5, 5' and 12, 12' in the manner already described. To remove the form from the garment, the clamp 32 of the lower separator 20 is released, and the base members 5 and 5' are again removed from the upper separator 19. The 65 base members 5 and 5' are then separately removed from the trousers legs, and the crease-forming members 12 and 12' are removed together, by using the upper separator 19 as a handle. It is to be understood that instead of a 70

5 screw means of removably securing the base members to the separator 19, any other suitable means may be used. Thus, also, it is possible to disassemble the separator 19 by removing the thumbscrew 32 and laterally disengaging the slide 27 and the member 21. By this means, the base members may be inserted into, and removed from, the garment, as a unit, the female member 21 serving as a handle.

10 It is to be understood also, that the terms "base-member" and "crease-forming member" as used in this specification, are interchangeable in all cases except those in which only one crease is to be formed in a garment. Thus, in the case 15 15 of a garment form for a pair of trousers, what has herein been described as a "crease-forming member 12" may itself be construed a "base member" with a crease-forming edge, and what has herein been described as a "base member 5" may 20 20 itself be construed as a "crease-forming member" without departing from the spirit of the invention. Moreover, my invention is adapted for use with any garment, and is not limited to the use thereof with trousers.

25 I am aware that the invention may be embodied in other specific forms without departing from the spirit or essential attributes thereof, and I therefore desire the present embodiments to be considered in all respects as illustrative 30 30 and not restrictive, reference being had to the appended claims rather than to the foregoing description to indicate the scope of the invention.

Having thus described my invention, what I

claim as new and desire to secure by Letters Patent, is:

1. A garment form comprising a base member and a plurality of crease forming members, a separator disposed intermediate said base and crease forming members; said crease forming members being adapted to be spaced from each other by the fabric of a garment, and said separator comprising a clamp adapted to clamp together said crease forming members and garment 10 fabric.

2. A garment form comprising a base member and a plurality of crease forming members, a separator disposed intermediate said base and crease forming members; said crease forming 15 members being adapted to be spaced from each other by the fabric of a garment; and said separator comprising a clamp adapted to clamp together said crease forming members and garment fabric, and friction means for removably securing said separator to at least one of said members.

3. A garment form comprising a base member and a plurality of crease forming members, a separator disposed intermediate said base and crease forming members, means to adjust the spacing between said base and said crease forming members; said crease forming members being adapted to be spaced from each other by the fabric of a garment, and said separator comprising 25 30 a clamp adapted to clamp together said crease forming members and garment fabric.

TOBIAS EISENBERG.
